UNITED STATES PATENT OFFICE.

WILLIAM LUCAS, OF MARKDALE, ONTARIO, CANADA.

SAWING-MACHINE.

SPECIFICATION forming part of Letters Patent No. 311,501, dated February 3, 1885.

Application filed July 24, 1884. (No model.) Patented in Canada June 23, 1884, No. 19,686.

To all whom it may concern:

Be it known that I, WILLIAM LUCAS, of the village of Markdale, in the county of Grey, in the Province of Ontario, Canada, banker, have 5 invented a certain new and useful Sawing-Machine; and I do hereby declare that the following is a full, clear, and exact description of the same.

The object of the invention is to devise a 10 portable machine by which a crosscut-saw may be operated with greater ease than when worked without the machine in question; and it consists, essentially, in connecting the cross-cut-saw to a frame arranged to guide it, and 15 also assist in starting the cut at each end of the stroke.

Figure 1 is a perspective view of the machine. Fig. 2 is an enlarged perspective detail of the rear guiding part of the frame. Fig. 20 3 is a perspective detail of the front guiding part of the frame.

A is a triangular base-frame, its apex being rigidly bolted to the front guiding-frame, B. This guiding-frame extends diagonally beyond 25 the legs C, which are connected at their base to the frame A and at their apex to the frame B, as shown.

D is a rear or back guiding-frame securely fastened to the frame A, as indicated, and arranged to receive and guide the bottom of the leg E, the upper end of which is connected to the frame B by the curved spring F. It will be noticed that the leg E passes through a slot in the bar G and moves freely within the said 35 slot, the said leg being pivoted to the bracket H, which, as shown, is fixed to the bar G.

I is the saw-handle, one end of which is pivoted to the bracket J, which is connected near the bottom of the leg E, as shown. This saw-40 handle I passes between the vertical bars K, and is fastened to the saw L, which saw passes through a slot made in the bottom of the frame B, which is therefore a guide for the saw.

Immediately above where the saw passes 45 through the frame B a friction-roller, M, is placed, on which friction-roller the bar G rests, so that when the said bar is worked back and forth with the saw the roller prevents any appreciable friction.

N is a triangular frame, the base of which 50 is pivoted to the legs C, and its apex is provided with a friction-roller, O, arranged to rest

upon the top edge of the saw L. This frame N is intended to provide means for adding weight to the saw, the said frame not only adding weight itself, but stones or other weights may be placed on top of the frame for increasing the weight, if desired. 55

By connecting the saw-handle to the foot of the leg E, I keep the saw down horizontally 60 to its work, while by placing the handles P on the bar G the operator can work the saw without stopping, although the power is conveyed directly behind the saw L, through its connection with the leg E, which is pivoted, 65 as before mentioned, on the bracket H, fastened to the bar G. Owing to the curved spring F the leg E receives a start at the commencement of each stroke—that is to say, when the leg E has been pressed close to the legs C, the 70 spring F will be compressed, and in regaining its form imparts a back-pressure to the leg E. When the opposite end of the stroke is reached, the spring F will be expanded, and imparts by its reverse action a back start for the leg E. 75 In this way the sawing is much easier, as the sawyer gets assistance at a time in the stroke when assistance is of the most benefit—namely, at the commencement of the stroke—and as the sawyer can operate the saw without stooping 80 he has much more power over it, and it is, moreover, much more easily worked.

In order to enable more than one to assist in sawing, I place on the bar G one or more handles, Q. A spike, R, is placed at the end 85 of the frame B, for the purpose of being driven into the log S, which log is further held to the saw-frame by the dog T.

What I claim as my invention is—

1. In combination, the guide-bar G, bracket 90 H, attached thereto, leg E, pivoted between its ends to said bracket, one of said ends being connected with the saw, and the spring F, arranged to support the other end and give an impulse to the saw, substantially as described. 95

2. In combination with the saw L, handle I, frame B, and leg E, the reciprocating bar G, slotted at one end to admit of the passage of the leg E, and bracket H, the parts being constructed, arranged, and operating substantially as set forth. 100

3. The saw L, attached to the handle I, and deriving a reciprocating motion, as specified, in combination with the triangular bar-frame

N, pivoted to the main frame of the machine, and provided with a friction-roller, O, slotted guide-frame B, vertical guide-bars K, and frame D, the parts being arranged and operating for the purpose specified.

4. The frame B, provided with means for securing and holding a log, S, in combination with the saw L, leg E, and bar G, reciprocat-

ing in and guided by the frame B, as specified, and actuating the leg E, substantially as to and for the purpose set forth.

Markdale, June 10, 1884.

WILLIAM LUCAS.

In presence of—

WILLIAM L. YOUNG,
THOMAS MENEA.
